UNITED STATES PATENT OFFICE

JOHN J. CRAIN, OF WATERBURY, CONNECTICUT, ASSIGNOR TO THE WATERBURY TOOL COMPANY, OF WATERBURY, CONNECTICUT, A CORPORATION OF CONNECTICUT

DRIVING MECHANISM FOR ROTARY DRILLING MACHINES

Application filed June 24, 1927. Serial No. 201,073.

The principal object of this invention is to provide a new and improved construction for the driving mechanism of rotary drilling machines of the type employed for the drilling of oil wells. In the drilling of oil wells, great differences occur in the resistances offered both to the rotation of the drill and the feed thereof, because of the different strata of material i. e. rock, sand, mud, clay, etc. of which the earth is composed. Consequently it has been a problem of great difficulty to provide a driving mechanism capable of compensating for the differences in resistances which the drill must overcome. In order to secure the best results it is desirable that the driving mechanism be so constructed that first: the drill will be subjected to an approximately constant uniform torque thereby avoiding the danger of its breaking or twisting off, second, that the rate of feed will be governed automatically by the resistance encountered by the drill, and third, the drill will be automatically raised or relieved when sticking thereof occurs.

The present invention has for its object to produce a driving mechanism that will fulfill the conditions above enumerated. A further object is to provide a hydraulic speed gear equipment adapted to be so combined with the drilling machine that the apparatus will operate automatically to compensate for differences in resistance offered to the drill by different materials. Other more specific objects will appear from the description hereinafter and the features of novelty will be pointed out in the claims.

In the accompanying drawings forming a part hereof Fig. 1 is a plan view of a rotary drilling machine equipment embodying the principles of my invention, Fig. 2 is a side elevation, and Fig. 3 is a side elevation partly in section of an A-end unit of a hydraulic speed gear of the type above described.

As shown in the drawings, the numeral 10 indicates the base of the drilling machine proper, which base has rotatably mounted therein the rotary drill table 11. The table 11 has secured thereto a bevel gear 12 driven by the bevel pinion 13; the latter being secured to the shaft 14 of a hydraulic gear

motor unit or B-end 15 secured to said base 10.

The table 11, in accordance with the usual construction of devices of the type to which this invention relates, is provided with a non-circular, central, through, aperture in which is slidably received the drill rod 16. Secured to the lower end of said drill rod is the drill bit 17 while the upper end of said rod has fastened thereto an eye bracket 18 with which the drill hoisting tackle is engaged.

Any suitable mechanism may be employed for the hoisting tackle; as shown such tackle consists of a pair of pulley blocks 19, 20, through which the hoisting cable 21 is trained, the block 19 being provided with the usual hook 19^a from which the drill rod 16 is suspended by the eye bracket 18. One end of the cable 21 is anchored to the block 19 and the other end thereof is trained about the winch 22. The winch 22 is driven, through the gears 23 by means of a small hydraulic gear unit or A-end 24, having an adjustable control shaft 25.

The B-end 15 and the small A-end 24 are connected in parallel to the pipe lines 26 and 27 through which fluid under pressure is circulated by a main pump unit or A-end 28, the latter being connected with said pipe lines by the connecting pipes 29, 30. The main A-end 28 is provided with an adjustable control shaft 31 and is driven by any suitable means such as an electric motor 32.

As shown in Fig. 3 of the drawings each gear unit comprises a rotary barrel 35 having a plurality of cylinders 36 formed therein, in which cylinders, pistons 37 are mounted for reciprocation. The pistons 37 are connected by means of the piston rods 38 with a member 39, known in the art, as a swash-plate. The swash-plate is mounted for rotation within a tilting box 40 having a projecting stub shaft 41. To the end of the stub shaft 41 is connected the lower end of a control shaft 42, the upper end of which is threaded and projects through the casing of the unit. Engaged upon the threaded upper end of the control shaft 42 is a nut 43 having a hand wheel portion 44. Rotation of the

hand wheel 44 and nut 43 will produce a vertical adjustment of the control shaft and a corresponding change in the inclination of the tilting box and swash-plate. When the 5 tilting box is perpendicular to the axis of rotation of the barrel 35 no stroke of the pistons 37 occurs and the gear is in "neutral" position. When the tilting box is inclined to the axis of rotation of the barrel 35 and the barrel 10 is rotated, the pistons 37 will be reciprocated within the cylinder 36, the extent of reciprocation depending upon the degree of inclination of the tilting box; the greater the inclination the greater the stroke. In- 15 clination of the tilting box in one direction causes the fluid to be pumped by the pump unit in a given direction whereas inclination of the box in the opposite direction causes the direction of the flow of the fluid to be re- 20 versed. In the motor unit of a gear of this type, the tilting box is usually held at a fixed angle of inclination and therefore the adjustable control shaft is not ordinarily used with the motor unit. In the pump unit how- 25 ever, the adjustable control shaft 42 is em- ployed. An example of the type of hydraulic gear is disclosed in United States Patent #925,148 of June 15, 1909, Harvey D. Wil- liams, variable speed gear.

30 The operation is as follows: The electric motor 32 being placed in rotation, will drive the main A-end 28 by means of which fluid will be pumped to the pipe lines 26, 27 at a rate depending upon the setting of the control shaft 31. Fluid under pressure is circu- 35 lated from the main A-end 28 through the pipes 26, 27, 29 and 30 to the small A-end 24 and the B-end 15. The B-end 15 will be driven by such fluid and its shaft 14 will 40 rotate, through the gears 12, 13, the drill table 11 and the drill rod 16. For ordinary drilling the control shaft 25 of the A-end 24 will be set so that a sufficient tension will be maintained on the cable 21 to offset or bal- 45 ance the weight of the drill rod to the re- quired extent according to the amount of feeding pressure desired. As the drill moves downwardly under such pressure and the cable 21 pays out thus rotating the winch 50 drum, and the shaft of the A-end 24, the latter acts as a pump and feeds fluid under pressure to the pipe lines 26, 27. If the drill should stick, the pressure of the fluid in the B-end 15 obviously will mount and the fluid, 55 following the lines of least resistance will be pumped to the A-end 24 driving it as a motor and causing the winch to operate the hoist- 60 ing tackle in a direction to raise or relieve the drill. When the drill meets with but slight 65 resistance and runs down more rapidly, the overhauling of the A-end 24 by the winch causes said A-end 24 to operate as a pump and to deliver fluid under pressure to the line thus causing the B-end 15 and drill to be ro- tated more rapidly, while, when harder, or

more resistant material is encountered, the drill will not run down as rapidly, therefore, the pumping action of the A-end 24 will decrease or will be neutralized, and as the pressure in the B-end 15 increases the A-end 24 70 will operate as a motor to raise the drill. It will thus be seen that if the torque required to rotate the drill increases, the increased oil pressure will operate, back through the line to the A-end 24, to raise or relieve the drill 75 and prevent increase of the torque beyond a predetermined amount whereas when the drill works easily and the oil pressure lowers, the drill will descend more rapidly thus tending again to restore the torque to its normal 80 amount. Consequently, an approximately uniform, and accurately predetermined torque can be maintained upon the drill, which torque is controllable by the adjustment or setting of the control shaft 25 of the A-end 85 24 while at the same time the normal speed of rotation of the drill can be regulated by the adjustment of the control shaft 31 of the A-end 28. As the well becomes deeper and the weight of the drill is increased by the use 90 of additional lengths of drill rod, the number of leads in the hoisting tackle can be increased so that constant oil pressure can be maintained with a variation in the control setting of the small A-end 24 of not much 95 more than 2 to 1, that is, from full stroke to half stroke. Within this range the A-end 24 will work satisfactorily both as a hydraulic motor and as a hydraulic pump.

While I have shown the invention as applied to a rotary, oil well, drilling machine it will be understood that the invention is not limited in its application to this specific type of machine but that it may be used in other installations wherein it is desirable to obtain a balanced or proportional relationship between torque and feed. It will also be understood that many changes, variations and modifications may be resorted to without departing from the spirit of the invention.

I claim:

1. The combination with a drilling machine having a rotary drill and a hoisting mechanism, of a fluid pressure pump and a pair of fluid pressure gear units connected in parallel with said pump, one of said units being connected with said drill for rotating it and the other of said units being connected with said hoisting mechanism and being operated convertibly as a pump or as a motor automatically in accordance with the resistance offered to the rotation of said drill.

2. The combination with a tool mounted for longitudinal and rotary movement, of a pair of fluid pressure gear units operatively associated with said tool, one of said units effecting the rotary movement and the other the longitudinal movement of said tool, of a main fluid pressure pump, and piping connections between said pump and units where- 13

by the resistance encountered to the rotation of said tool will be communicated through said fluid to the said other of said units to produce rotation thereof.

5 3. The combination with a rotary cutting tool, of a pair of fluid pressure gear units operatively associated with said tool, one of said units exerting a torque upon said tool and the other governing the rate of feed of 10 said tool to the work, and pipe connections between said units for causing the operating fluid to be circulated to said units in accordance with the resistances offered to the movements of said tool.

15 4. The combination with a cutting tool, of a rotary fluid pressure actuated driving gear to rotate said tool, and means to cause said gear to maintain a substantially uniform torque upon said tool, said means including 20 a second rotary fluid pressure actuated driving gear for regulating the rate of feed of said tool to the work.

25 5. The combination with a cutting tool, of a rotary fluid pressure actuated driving gear to rotate said tool, and means to cause said gear to maintain a substantially uniform torque upon said tool, said means including a second rotary fluid pressure actuated driving gear of adjustable effect for regulating 30 the rate of feed of said tool to the work.

35 6. The combination with a rotary cutting tool, of a rotary fluid pressure actuated driving gear to rotate said tool, a second rotary fluid pressure actuated gear for regulating the feed of said tool to the work, a common pump for supplying fluid under pressure to said driving gears and pipe connections interconnecting both of said gears and said pump.

40 7. The combination with an oil well drilling machine having a rotary drill and hoisting mechanism therefor, of a fluid pressure actuated motor associated with said drill for rotating it, a fluid pressure actuated gear unit adapted to function as a motor or as a pump, operatively associated with said hoisting mechanism, a pump for circulating fluid under pressure to said motor and gear unit and piping interconnecting said motor, said 45 gear unit and said pump.

50 8. The combination with an oil well drilling machine having a rotary drill and hoisting mechanism therefor, of a fluid pressure actuated motor associated with said drill for rotating it, a second fluid pressure actuated device, capable of being operated either as a pump or as a motor, connected with said hoisting mechanism, and a pump for supplying fluid under pressure simultaneously to said 55 motor and to said device, said device being provided with means for varying its effect.

95 9. The combination with an oil well drilling machine having a rotary drill and hoisting mechanism therefor, of a fluid pressure actuated motor associated with said drill for

rotating it, a second fluid pressure actuated device, capable of being operated either as a pump or as a motor, connected with said hoisting mechanism, and a pump for supplying fluid under pressure simultaneously to 70 said motor and to said device, said pump and said device each being provided with adjustable controlling means, the variation of the controlling means for said pump effecting speed changes in the rotation of said drill and 75 the variation of the controlling means for said device effecting the rate of feed of said drill.

10 10. The combination with an oil well drilling machine having a rotary drill and hoisting mechanism therefor, of a fluid pressure actuated motor associated with said drill for rotating it, a second fluid pressure actuated device, capable of being operated either as a pump or as a motor, connected with said 15 hoisting mechanism, and a pump for supplying fluid under pressure simultaneously to 80 said motor and to said device, said pump and said device each being provided with adjustable controlling means, the variation of the 85 controlling means for said pump effecting speed changes in the rotation of said drill and the variation of the controlling means for 90 said device effecting the rate of feed of said drill and piping interconnecting said pump 95 motor and device whereby a mutual interdependence of operation of said motor and device is secured and a substantially uniform torque is imparted to said drill.

100 11. The combination with an oil well drilling machine having a rotary drill and hoisting mechanism therefor, of a fluid pressure actuated motor associated with said drill for rotating it, a fluid pressure actuated device 105 capable of operating either as a pump or as a motor, operatively associated with said hoisting mechanism, suction and pressure pipe lines connecting said motor and said device whereby variations of the pressure conditions 110 in said motor due to changes of resistance offered to the rotation of said drill will be communicated through the fluid in said pipe lines to said device, and a pump for supplying fluid under pressure to said motor.

In testimony whereof I have hereunto set my hand.

JOHN J. CRAIN.
